CHECK INDORSING AND SIGNING
MACHINEHjalmar A. Swanson, Chicago, Ill., assignor to
Cummins Perforator Company, Chicago, Ill., a
corporation of Illinois

Application September 8, 1931, Serial No. 561,537

26 Claims. (Cl. 101—236)

The invention relates generally to printing mechanism having more particular reference to improvements in check signing and indorsing machines.

5 Machines of the above class are characterized by a type carrying member in association with an impression member between which a work sheet or check, as the case may be, is passed for performing a printing operation. The type 10 member, in accordance with the present invention, is intermittently rotated from a continuously rotating power shaft by means of a novel form of clutch with the rotations being initiated by a work sheet or check actuating a tripping 15 device when the same is dropped into the feed opening of the machine. The machine comprises in two sections or compartments supported on the same base, one containing the printing element such as the ink reservoir, type carrying cylinder and power means, preferably an electric 20 motor, and the other section journaling the impression cylinder and providing a receptacle and stacking member for the printed sheets. With respect to this latter feature it has been found desirable to stack the printed checks in such a 25 manner that they will be in the same order with relation to each other as they were before being fed to the machine. Novel means are provided 30 adapted to cooperate with the stacking member for accomplishing this result.

The invention has for its general object to provide an improved type of machine adapted for light printing work such as signing or indorsing checks, which will be simple in construction, efficient and positive in operation and designed to fulfill all service requirements.

40 A further object is to provide a machine of the character described in which the intermittently rotating type carrying member is driven from a continuously rotating power shaft by means of an improved clutch construction, actuation of the clutch being accomplished automatically by the insertion of the sheet for printing.

45 A further object is to provide a combination and arrangement of parts including a continuously rotating clutch wheel and cooperating pawl, the latter being automatically thrown into engagement to initiate a printing operation, provision being made for disconnecting the pawl at the completion of one revolution of the clutch wheel.

50 A further object is to provide a stacking member for supporting the printed checks or work sheets in vertical position substantially as delivered from the printing mechanism and which

will yieldingly support the same and have movement to accommodate an increasing number.

5 A further object is to provide a machine having a novel arrangement of parts which will insure the horizontal positioning of the checks or work sheets to be printed before actuation of the type carrying cylinder takes place. As a result of the above the checks pass through the machine in horizontal alignment irrespective of their angular position when presented.

10 A further object is to provide means rotating with the type cylinder and operative to engage each printed check to position the same in proper stacked relation with the other checks supported by the stacking member. The checks that are 15 indorsed are stacked vertically by the instrumentalities above described and the checks that are signed are stacked horizontally. The invention therefore provides additional means which when rendered operative will stack the checks 20 horizontally.

25 A further object is to provide a device wherein the constructional arrangement of the parts will permit access to be had for cleaning purposes and which will coordinate their various functions in such a manner as to result in efficient operation.

30 With these and various other objects in view, the invention may consist of certain novel features of construction and operation as will be 35 more fully described and particularly pointed out in the specification, drawings and claims appended hereto.

35 In the drawings which illustrate an embodiment of the device and wherein like reference characters are used to designate like parts—

Figure 11 is a detail sectional view taken along line 11—11 of Figure 3 showing the means for releasably locking the type cylinder in position.

10 The embodiment selected for illustration in the drawings includes, as shown in Figures 2 and 3, a frame or housing formed of two sections on a common base 10, one section comprising side members 11 and 12 and end member 13, an end plate 14 and a top plate 15 having pivotally secured thereto a member 16, and the other section comprising side members 17 and 18 and end member 20 and a top plate 21. This latter section forms a receptacle for receiving the printed 15 work sheets and accordingly the side members and the end member have portions cut therefrom so as to allow access to the same. The portion 16, as shown in Figure 4, has detachably secured thereto a paper guard 22 by means of depending pins secured to the guard insertible in the bosses 23 provided on the undersurface of the portion. In like manner the top plate 21 has detachably secured thereto a paper guide 24 by means of depending pins 25 fitting within bosses 26.

20 The section formed by the side members 11 and 12, the end member 13 and top plate 15 houses the printing member and means whereby the same is rotated to complete a printing operation when a work sheet has been properly positioned with respect to the member. The power 25 means is included in an electric motor 27 suitably secured to a support 28 and providing a driving shaft in the form of a worm 30. The worm is adapted to drive through mechanism, which will

30 be presently described in detail, a type carrying cylinder including a body portion 31 carrying any suitable form of type such as 32, and circular end members 33 and 34. The shaft 35, rotatably mounted in the respective side members 11 and 12 through means of ball bearing races 36, has suitably mounted thereon the type carrying cylinder and by means of which the cylinder is journaled in the frame. Projecting outwardly from the left hand end of the shaft, 35, are actuating discs 37, so that the indicia on the type cylinder, such as the date and batch number, can be changed from day to day. Meshing directly with the worm 30 is a worm gear 40 suitably keyed to shaft 41 journaled at one end 35 by means of the ball bearing race 42 and the side member 12, and at its other end in the partition 43 suitably secured to base 10. The shaft 41 forms a driving means for the inking roller 44 provided with central tube 45 secured to the

40 end members 46. Projecting from one end of tube 45 and non-rotatably secured thereto is a stud 47 on which is mounted gear 48 and the ball bearing race 42, the latter adapted to be removably positioned in the side frame 11. Projecting from the other end of tube 45 is a stud 50, non-rotatably secured to the tube by means of the pin 51 extending through the shaft and slot 52 formed in the tube and being resiliently urged outwardly by the coil spring 53.

50 To the outer projecting end of the stud shaft 50 is rigidly secured the hub disc 54 provided with a plurality of openings for receiving the projecting studs 55 secured to a companion hub disc 56 mounted on a projecting end 57 of the driving shaft 41. The projecting end is suitably centered

in the disc 54 and thus provides a continuation with the shaft 50 of the means by which the roller 44 is journaled in the frame. By the above construction the inking roller can be removed to permit cleaning of the same as the ball bearing race 42 is removable from frame 11 with the disc 54 being detachable from its companion disc 56.

5 The inking roller is adapted to receive ink from a reservoir 58 having a filling cap 59 and being 10 removably secured within the frame by means of the securing screw 60, Figure 3. The reservoir has suitably journaled therein a cylinder 61 mounted on shaft 62 to which is secured the gear 63 having meshing engagement with gear 48 so 15 that the cylinder is driven from the driving shaft 41. For removing the surplus ink from the cylinder 61 and to distribute ink evenly over the cylinder there is located within the reservoir a member 64 extending the length of the cylinder and 20 supported on studs 65 mounting the springs 66 which resiliently urge the member toward the cylinder. Supported by the member 64 is a 25 length of felt or other suitable material 67 which has engagement directly with the surface of the cylinder 61 and thus forms the ink retrieving means. The ink picked up by cylinder 61 is distributed evenly over the surface of the same and transferred to the inking roller 44 engaging therewith, which in turn transfers the proper 30 amount of ink to the indicia 32 on the type cylinder. In order to adjust the pressure between the cylinder and the roller the reservoir is provided with bosses 68 which abut the adjustable set 35 screws 69 located in the support 70. By varying the extent to which the ends of the set screws project from the support the position of the reservoir with relation to the inking roller can be adjusted.

35 The type cylinder 31 is rotated intermittently 40 from the driving shaft of the electric motor through means of clutch mechanism, the mechanism being actuated to operatively connect the type cylinder with the driving shaft automatically by the work sheet to be printed. 45 The structure for accomplishing the above includes, as shown in Figure 4, a tubular driving shaft 71, rotatably mounted on shaft 35 and having suitably keyed to one end the gear 72 with a clutch wheel 73 formed integral with the other 50 end. The partition 43 is formed to provide a support for the tubular shaft 71 and frictionlessly mount the same for rotation by means of the ball bearing race 74. The clutch wheel 73 is driven continuously by the electric motor and imparts 55 continuous rotation to the roller 75 engaging therewith, the roller being suitably secured to shaft 76 mounted for rotation, as shown in Figures 2 and 7, in pivotally supported bearings 77. The shaft 76 supports the impression cylinder 78 in position adjacent the type cylinder 31 but suitably spaced therefrom so that the impression cylinder may continuously rotate while the type cylinder is held stationary. It will be clear that 60 the type or indicia secured to the type cylinder projects sufficiently from the surface of the same to be engaged by the impression roller so that a printing operation takes place when a sheet of paper is positioned therebetween. The transverse rod 79 is suitably supported by the side members 17 and 18 and forms means for supporting the bearings 77, which are resiliently urged 65 in a direction maintaining roller 75 in engagement with clutch roller 73 by the springs 80 secured at one end to the upper portion of the bear- 70

75

ings, respectively, and at their other end to a second transverse rod 81. To properly locate the pivotally supported bearings 77 so as to properly position the impression cylinder 78 a projection

5 82 is formed on each bearing and receives an adjustable set screw 83 adapted to engage the rod 81 which acts as a limiting stop.

The clutch mechanism for operatively connecting the type cylinder with the clutch wheel, Figures 8 and 9, includes a pawl 85 pivotally secured by the stud 86 to the end member 34 of the type cylinder and ratchet teeth 87 formed on the interior surface of the clutch wheel. Formed integrally with the pawl 85 and also pivotally mounted on stud 86 is an actuating arm 89 and a clutch release arm 88 having a notch provided therein for engagement with the spring pressed 10 detent 90 suitably mounted on the type cylinder, the actuating arm projecting substantially in an opposite direction from the release arm 88, that is, toward the impression cylinder, so that the arm is located in the path of a sheet of paper being positively fed by engagement with clutch wheel 73 and roller 75. Positioned to the left of the type cylinder is a support 91 having a projecting flange 92 secured thereto at its lower end and pivotally mounting at 93 a locking lever 94, Figure 11, which is spring pressed toward the right by a coil spring 95. The bulbous portion 15 96 formed integral with the locking arm extends into the path of the clutch release arm 88 as does the flange 92. The locking lever extends to a point substantially midway of the flange 92 and is adapted to engage a stop 97 provided on the periphery of the type cylinder. With the stop 20 in engagement with locking lever 94 and with the detent lever 98 pivoted to the frame at 99, Figure 2, located in the notch 100 formed in end member 33 of the type cylinder, the type cylinder 25 and shaft 35 are securely held stationary.

It will be clear, however, from the structure described that the clutch wheel 73 is being rotated on shaft 35 through the meshing of gear 72 with the worm 30 on the driving shaft of the motor. This is permitted by the position of the clutch mechanism, as shown in Figure 8, wherein the pawl 85 is disengaged from the teeth 87 and the release arm 88, although contacting the bulbous portion 96 integral with the locking arm 94 permits the arm to abut the stop 97 on the type cylinder.

To operate the device a sheet of paper or check is first inserted in the throat formed by the depending flanges 101 and 102 provided on portion 16 and the top plate 21, respectively, which positions the sheet between the type cylinder and the impression cylinder, and between the clutch wheel 73 and the roller 75. Engagement of the sheet by the constantly rotating means functions to positively feed the sheet downwardly so that the leading edge of the sheet engages the actuating arm 89 of the clutch mechanism. Continued downward movement of the leading edge of the sheet will rock the actuating arm, pawl 85 and release arm 88 integral therewith. Movement of the pawl and release arm is in an upward direction, Figure 8, which simultaneously disengages the arm 94 from stop 97 and engages the pawl with the teeth 87. The release of the type cylinder from the locking lever 94 is caused by rotation imparted to portion 96 by the release arm 88, which is sufficient to rotate the arm out of the path of stop 97. The cylinder is thus released 20 for rotation at substantially the same time that

the pawl 85 engages the teeth of the rotating clutch wheel 73 and since the pawl is pivotally secured to the type cylinder, rotation of the cylinder takes place.

The sheet or check being printed has by this time been fed by the rotation of the parts so that its leading marginal edge is positioned between the printing cylinders. As continued rotation takes place the indicia on the type cylinder contacts the fed sheet and through the pressure exerted by the impression cylinder 78 printing of the sheet is accomplished. Subsequently to this operation the printed sheet is ejected from the rotating cylinders but before the type cylinder completes one revolution the release arm 88 5 will strike the projecting flange 92, throwing the pawl 85 out of engagement with the teeth 87. A positive throw-out is necessary for the clutch mechanism since the release arm by the detent 90 is held in that position to maintain engagement 10 between pawl 85 and the clutch teeth. With the clutch mechanism disengaged the momentum of the rotating type cylinder is sufficient to cause rotation of the cylinder until stop 97 engages the locking lever 94, whereupon the detent lever 98 15 will drop into notch 100, holding the cylinder and shaft 35 from further rotation until the next sheet to be printed actuates the clutch to initiate another printing operation.

Referring particularly to Figure 7 the frame 30 which provides a receptacle for receiving the printed sheets is shown equipped with a stacking member 105 including arms 106 secured at their upper end to transverse rod 81 and joined at their lower end by the metal strip 107. The rod 81 35 is rotatably mounted within the frames 17 and 18 and is resiliently urged in a direction so that the printed sheets will be supported by the metal strip 107 in substantially vertical filing order by spring 108 having its end secured to the frame 40 and the right hand arm 106, respectively, Figure 3. In combination with the stacking member 105 means are provided which function to positively locate each printed sheet in correct position, including the transverse shaft 110 journaled 45 at its ends by the ball bearings 111 in side members 11 and 12, respectively, Figure 4, and on which is suitably mounted the sprocket 112 adapted to mesh with chain 113 in turn engaging sprocket 114, non-rotatably mounted on shaft 50 35. As the shaft 35 is rotated by the rotations of the type cylinder the same are imparted to shaft 110 so that the construction serves to rotate the arcuate arms 115 mounted in spaced relation on the shaft 110. The arms project 55 through vertical slots 116 provided for the purpose in the face plate 14 and engage the printed sheet, positioning the sheet in the pile supported by the stacking member 105. By this structure the order in which the sheets are printed is maintained in the stacking of the same and as the pile of printed sheets increases the stacking member is forced in a direction toward the right, Figure 7, until the limit of the receptacle is reached.

The present machine is adapted to sign checks 65 in addition to indorsing them and for the former purpose it is necessary to deposit the sheets horizontally instead of in the vertical filing order above described and shown in Figure 7. Accordingly, the present invention provides, Figure 2, 70 a removable tray 117 having suitably secured thereto at one end a vertical partition 118 and adapted to be inserted in the frame defined by the side members 17 and 18 in position below the rod 81 and so that the stacking member 105 en- 75

gages the right hand end of the same. For catching the sheets as they are ejected from the printing cylinders so that they are deposited on the tray 117 horizontally there is journaled in the side members 11 and 12, as shown in Figure 5, a rotatable shaft 120 having mounted thereon in spaced relation the curved arms 121 and being provided with an operating knob 122. The coil spring 123 mounted on the rotating shaft serves 10 to urge the shaft toward the right so that the pin 124 is held in the opening 125 formed in the side member 11, positioning the arm substantially horizontally. By grasping the knob 122 and drawing the shaft to the left the pin can be withdrawn 15 from the opening and the shaft rotated to locate the arms in their inoperative position. The arms 121, as shown in Figure 2, are in position for receiving the sheets as they are ejected from the printing cylinders as has been described. 20 The leading edge of the printed sheet in striking the arms is directed toward the right, as shown in Figure 2, and simultaneously assumes a horizontal position. The printed sheet is then deposited by gravity upon the pile supported by 25 the tray 117. This construction permits the insertion of checks with their faces toward the type cylinder, which is necessary for the signing of the same, and still maintains the printed checks in the same filing order they assumed 30 before printing. The check is accordingly turned substantially 90 degrees after it is ejected from the cylinders and before depositing upon the tray, which is accomplished by the above structure efficiently, with the additional feature that the 35 structure is removable so that the machine can be easily converted to the vertical stacking of the printed checks required when they are indorsed.

A feature of the present invention is the provision of means which insures that the checks or sheets although inserted in the machine in an angular position will pass through the machine for printing in substantially horizontal alignment. This is accomplished by securing a lug 126 to the end member 33 of the type cylinder and pivotally mounting a finger 127 on the frame and locating the same in the path of the sheets or checks to be printed. As shown in Figures 3 and 10 the finger 127 is positioned to the right of the type cylinder and is pivotally secured at 128 to the vertical partition 43. The arm is resiliently urged in a direction to locate its end in a notch 130 in the right hand bearing 77 by the coil spring 131 secured to the upper end of the arm at 132 and to a pin 133 provided on the pivoted lever 134. The lever is locked in a downward position so as to maintain tension on the spring 131 by means of the depending pins 25 provided on the paper guard 22. Should the check or sheet of paper which is to be printed be dropped by the operator between the flanges 101 and 102, as would ordinarily be the case, the check or sheet will automatically be righted prior to the locationing of its leading edge between the clutch wheel 73 and roller 75, which function as has been described, to cause positive feeding of the same. If the check assumes an angular position with respect to the type cylinder the leading edge will either engage the lug 126 or the finger 127. In both instances the supported end of the check will be held by the abutment but since the operator no longer has control of the check the free end will drop, whereupon the check assumes a substantially horizontal position. In this position it will be seen that the

leading edge will be located between the clutch wheel and the roller and as these members are continuously rotated the sheet will be engaged and positively fed through the machine automatically actuating the clutch to initiate the printing operation.

It is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

I claim:

1. A device of the character described, in combination, a frame, a shaft journaled in the frame and having a type cylinder mounted thereon, a clutch wheel mounted on said shaft for rotation, a clutch pawl pivoted to the type cylinder and adapted to releasably engage said clutch wheel, a detent for holding the pawl in engaged position, and an actuating arm secured to the pawl.

2. A device of the character described, in combination, a frame, a shaft journaled in the frame and having a type cylinder mounted thereon, a clutch wheel mounted on said shaft for rotation, internal ratchet teeth on said wheel, a clutch pawl pivoted to one end of the type cylinder and adapted to engage said teeth, an actuating arm secured to the pawl, and means for causing disengagement of the pawl.

3. A device of the character described, in combination, a frame, a shaft journaled in the frame and having a type cylinder mounted thereon, a clutch wheel mounted for rotation on said shaft, an impression cylinder journaled in the frame for cooperating with the type cylinder, a clutch pawl pivoted to the type cylinder and having an actuating arm extending therefrom, said arm being engaged by a sheet inserted between the cylinders causing the pawl to engage the clutch wheel.

4. A device of the character described, in combination, a plurality of rotatably mounted printing cylinders including a type cylinder, a shaft for mounting said type cylinder, a clutch member adapted to rotate on the shaft, a pawl pivoted to the type cylinder and having a projecting actuating arm, and means for releasably locking said type cylinder in set position, said arm being actuated by a fed sheet to cause actuation of the pawl and rotation of the type cylinder.

5. A device of the character described, in combination, a plurality of rotatably mounted printing cylinders including a type cylinder, a shaft for mounting said type cylinder, a clutch member adapted to rotate on the shaft, a pawl pivoted to the type cylinder and having a projecting actuating arm, said arm being actuated by a fed sheet causing the pawl to engage the clutch wheel and rotate the type cylinder, and means for releasing the pawl.

6. A device of the character described, in combination, a plurality of rotatably mounted printing cylinders including a type cylinder, a shaft for mounting said type cylinder, a clutch member adapted to rotate on the shaft, a locking arm for preventing rotation of the type cylinder, a clutch pawl secured to the type cylinder and adapted to engage the clutch member for connecting the type cylinder with the clutch member, an actuating arm for the pawl, and a release arm for disengaging the pawl.

7. In a check signing and indorsing machine,

- in combination, a frame journalling a type carrying member, an impression member cooperating therewith, a driven shaft, a clutch positioned between said shaft and the type carrying member and including a pawl pivoted to and rotating with the type carrying member, said pawl being engaged by a sheet as the same is fed to the members to cause rotation of the type carrying member by the driven shaft.
10. 8. In a check signing and indorsing machine, in combination, a frame journalling a type carrying member, an impression member cooperating therewith, a driven shaft, a clutch positioned between said shaft and the type carrying member and including a clutch wheel rotating with the shaft and a pawl pivoted to and rotating with the type cylinder, said clutch wheel providing the driving means for said impression member and said pawl being engaged by a sheet as the same is fed to the members to cause rotation of the type member by said driven shaft.
9. In a check signing and indorsing machine, in combination, a frame journalling a type carrying member, an impression member cooperating therewith, a driven shaft, a clutch positioned between said shaft and the type carrying member and including a ratchet wheel rotating with the shaft and a pawl pivoted to and rotating with the type cylinder, said pawl being actuated by a sheet as the same is fed to the members to cause rotation of the type carrying member by the driven shaft, and means contacting said pawl to disengage said pawl upon the substantial completion of one revolution of the type member.
30. 10. In a check signing and indorsing machine, in combination, a frame, a shaft journalled in the frame and having a type cylinder mounted thereon, a clutch wheel mounted on said shaft for rotation and having operative connection with means for continuously rotating said wheel, a clutch pawl pivoted to the type cylinder and adapted to engage said clutch wheel for operatively connecting the type cylinder with said clutch wheel, and locking means holding the type cylinder against rotation, said locking means being automatically released by movement of said pawl in engaging with the clutch wheel.
11. In a check signing and indorsing machine, in combination, a frame journalling a type carrying member, an impression member cooperating therewith, a driven shaft, a clutch wheel mounted on said shaft for rotation and connecting with power means for continuously rotating the same, a clutch pawl pivoted to the type cylinder and adapted to engage said clutch wheel to cause rotation of the type cylinder, an actuating arm associated with said pawl and projecting between the members in the path of the fed sheet, and locking means holding the type cylinder against rotation in one direction, said locking means being released by the action of said pawl in engaging said clutch wheel.
12. In a check signing and indorsing machine, in combination a frame, a shaft journalled in the frame and having a type cylinder mounted thereon, a clutch wheel mounted on said shaft for rotation and operatively connecting with power means continuously rotating the same, a clutch pawl pivoted to the type cylinder and adapted to engage the clutch wheel to cause rotation of the type cylinder, an actuating arm associated with the pawl, means fixed to the frame for contacting with said pawl to disengage the pawl upon the substantial completion of one revolution of the type cylinder, and locking means holding the type cylinder against rotation in one direction, said means being released by the action of the pawl in engaging the clutch wheel.
13. In a check signing and indorsing machine, in combination, a frame journalling a type carrying member, an impression member cooperating therewith, a driven shaft, a clutch positioned between said shaft and the type carrying member, means actuating said clutch to operatively connect the driven shaft with the type carrying member, and locking means for holding the type carrying member against movement, said actuating means being engaged by a sheet as the same is fed to the members to cause release of said locking means and then rotation of the type member.
14. In a check signing and indorsing machine, in combination, a plurality of rotatably mounted printing cylinders including a type cylinder, a shaft for mounting said type cylinder, a clutch wheel adapted to rotate on the shaft and connecting with power means continuously rotating the same, a clutch pawl secured to the type cylinder and adapted to engage the clutch wheel for causing rotation of the type member, an actuating arm for the pawl, and release means for contacting the pawl to disengage the same upon the substantial completion of one revolution of the type member, said release means for the pawl being located in advance of the locking arm with respect to the direction of rotation of the type cylinder, whereby said clutch is released prior to engagement of the locking arm with the type cylinder.
15. In a check signing and indorsing machine, in combination, a plurality of rotatably mounted printing cylinders including a type cylinder, a shaft for mounting said type cylinder, a clutch wheel adapted to rotate on the shaft and connecting with power means continuously rotating the same, a clutch pawl secured to the type cylinder and adapted to engage the clutch wheel for causing rotation of the type member, an actuating arm for the pawl, a locking arm for holding the type cylinder against rotation, a release member for the locking arm adapted to be actuated by the pawl in advance of its engagement with the clutch member, and release means for contacting the pawl to disengage the same upon the substantial completion of one revolution of the type member, said release means for the pawl being located in advance of the release means for the locking arm.
16. In a check signing and indorsing machine, in combination, a type cylinder, an impression cylinder, shafts for journalling said cylinders in spaced relation, a clutch wheel mounted for independent rotation on the type cylinder shaft, means constantly rotating said clutch wheel, a roller secured to the impression cylinder shaft and rotated by engagement with the clutch wheel, and means positioned to the respective sides of said type cylinder for horizontally positioning a sheet inserted between the cylinders, one of said means being secured to an end of the type cylinder and rotating therewith.
17. In a check signing and indorsing machine, in combination, a frame, a type cylinder, an impression cylinder, shafts journalled in said frame for mounting said cylinders in proper relation, rollers contacting each other for feeding a sheet to the cylinders, one of said rollers comprising a clutch member and connecting with power means constantly rotating the same, a clutch pawl pivoted to the type cylinder and adapted

to releasably engage with said constantly rotating roller, an actuating arm associated with said pawl and projecting into the path of a fed sheet, and means positioned on each side of said type 5 cylinder and outwardly of said rollers for aligning a sheet horizontally before the sheet is engaged by the rollers, one of said means extending into the path of the fed sheet and being independent of the type cylinder.

18. In a check signing and indorsing machine, in combination, a frame journaling a type cylinder and an impression cylinder, rotating means for feeding the sheet of paper located between said cylinders, said cylinders being disposed to 10 receive a sheet substantially vertically and discharge the printed sheet in substantially vertical position, said frame providing means for receiving the printed sheets, and means including arcuate arms sloping downwardly at the ends 15 located over the receiving means and operating to receive the printed sheets and deposit them horizontally in the receiving means with the signed face downward, said means being retractile whereby the printed sheets may be deposited in the receiving means in substantially 20 vertical position as discharged from the printing cylinders.

19. In a check signing and indorsing machine, in combination, a plurality of rotatably mounted 30 printing cylinders including a type cylinder, a rotatably mounted shaft having said type cylinder fixedly mounted thereon whereby said shaft journals said cylinder, a clutch member mounted on said shaft for rotation independently 35 thereof and being normally disconnected from the type cylinder, means rotating said clutch member, a locking arm for holding the type cylinder against rotation in one direction, and means actuated by a sheet fed to the cylinders for releasing the locking arm to free the cylinder for 40 rotation and for operatively connecting the type cylinder with the clutch member to cause said cylinder to rotate with the clutch member, said operations taking place in sequence.

20. In a check signing and indorsing machine, in combination, a plurality of rotatably mounted printing cylinders including a type cylinder fixedly mounted thereon whereby said shaft journals said cylinder, a clutch member mounted on 50 the shaft for rotation independently thereof and being normally disconnected from the type cylinder, driving means for rotating said clutch member, a locking arm for holding the type cylinder against rotation in one direction, a latching lever 55 operative to hold the type cylinder against rotation and to prevent rebound when the type cylinder contacts the locking arm, and means actuated by a sheet fed to the cylinders for releasing the locking arm and for operatively connecting 60 the type cylinder with the clutch member to cause the type cylinder to rotate with the clutch member, said operations taking place in sequence and said type cylinder automatically displacing the latching lever upon initial rotation of the type 65 cylinder.

21. In a check signing and indorsing machine, in combination, a frame journaling a type cylinder and an impression cylinder, rotating means for feeding a sheet of paper located between said 70 cylinders, said cylinders being disposed to receive a sheet substantially vertically and discharge the printed sheet in substantially vertical position, said frame providing a receptacle for receiving the printed sheets, a pivotedly mounted stacking member depending from the frame and located 75

within the receptacle for supporting the printed sheets in substantially vertical position, a plurality of stacking arms mounted for rotation in said frame, said arms engaging each printed sheet individually to effect stacking of the sheet, and means rotating said stacking arms from the type cylinder, whereby said arms have intermittent rotation in timed relation with the printing operations performed by said cylinders.

22. In a check signing and indorsing machine, in combination, a frame journaling a type cylinder and an impression cylinder, rotating means for feeding a sheet of paper located between said cylinders, said cylinders receiving a sheet vertically disposed and discharging the printed sheet in substantially vertical position, said frame providing a receptacle for receiving the printed sheets, a pivotally mounted stacking member depending from the frame and located within said receptacle, means resiliently urging said stacking member in a direction to support the printed sheets in substantially vertical position, a plurality of stacking arms having curved ends and mounted for rotation in said frame, and means rotating said stacking arms to cause the curved ends thereof to engage with each printed sheet individually to effect stacking of the sheet.

23. In a check signing and indorsing machine, in combination, a frame journaling a type cylinder and an impression cylinder, rotating means for feeding a sheet of paper located between said cylinders, a receptacle for receiving the printed sheets, a shaft journalled in said frame and supporting a plurality of curved arms, said arms when disposed substantially horizontally and positioned in the path of the printed sheets causing the same to be deposited horizontally, said shaft being mounted for slidable movement in a direction axially thereof to permit rotation of the shaft to locate the arms in inoperative position, whereby the printed sheets may be deposited in the receiving means in substantially vertical position as discharged from the printing cylinders.

24. In a check signing and indorsing machine, in combination, a frame journaling a type cylinder and an impression cylinder, rotating means for feeding a sheet of paper located between said cylinders, said cylinders being disposed to receive the sheet substantially vertically and discharge the printed sheet in substantially vertical position, said frame providing a receptacle for receiving the printed sheets, a stacking member depending from the frame and located within said receptacle for supporting the printed sheets in substantially vertical position, a container adapted for location within said receptacle to hold the stacking member in inoperative position, and means located within said receptacle above the container and in the path of the discharged printed sheets to cause said sheets to be deposited horizontally in the container with their printed faces down.

25. In a check signing and indorsing machine, in combination, a frame journaling a type cylinder and an impression cylinder, rotating means for feeding a sheet of paper located between said cylinders, said cylinders being disposed to receive the sheet substantially vertically and discharge the printed sheet in substantially vertical position, said frame providing a receptacle for receiving the printed sheets, a stacking member pivotally supported from the frame and depending within said receptacle, means resiliently urging said stacking member in a direction to support the printed sheets in 75

substantially vertical position, a container adapted for location within said receptacle to hold the stacking member in inoperative position, and curved arms for location in said receptacle above the container and in the path of the printed sheets for causing said sheet to be deposited in said container horizontally with their printed faces down.

26. In a check signing and indorsing machine, in combination, a type cylinder, a rotatable shaft having said type cylinder mounted thereon, an impression cylinder, a shaft for jour-

naling said impression cylinder, a sleeve mounted for independent rotation on the type cylinder shaft, means constantly rotating said sleeve, a clutch member fixedly secured to said sleeve and positioned adjacent an end of said type cylinder, said clutch member having an annular flange provided with clutch teeth on the interior surface thereof, and a roller associated with the impression cylinder and driven from said clutch member through frictional engagement with the exterior surface of said flange.

HJALMAR A. SWANSON.
